UNITED STATES PATENT OFFICE.

LOUIS HANSON, OF COTTONWOOD, IDAHO.

WIRE-STRETCHER.

1,031,115.

Specification of Letters Patent.

Patented July 2, 1912.

Application filed July 13, 1911. Serial No. 638,304.

To all whom it may concern:

Be it known that I, LOUIS HANSON, a citizen of the United States, residing at Cottonwood, in the county of Idaho and State of Idaho, have invented certain new and useful Improvements in Wire-Stretchers; and I do hereby declare the following to be a full, clear, and exact description of the invention, such as will enable others skilled in the art to which it appertains to make and use the same.

This invention relates to wire stretchers and more particularly to means for stretching wire for fences.

15 An object is to provide a wire stretcher of the above stated character having a wire engaging portion which is adapted to be adjusted longitudinally for different widths of fence wire.

20 Other objects and advantages will be hereinafter set forth and pointed out in the specification and claims.

In the accompanying drawings which are made a part of this application, Figure 1 is an elevational view showing the device in operation. Fig. 2 is a detail cross sectional view through the adjustable wire engager, also through one of the wire grippers, and, Fig. 3 is a longitudinal sectional view through the adjustable wire engager taken on the line 3—3 of Fig. 1, the opposite ends of said adjustable engager being broken away.

Referring to the drawings in which similar reference numerals designate corresponding parts throughout the several views, 1 represents an auxiliary post to which is connected, by means of wire or other fastening devices 2, the vertical portion 3 of a bracket having the lower short horizontal arm 4 and the upper horizontal arm 5, which is somewhat longer than the arm 4 and also wider. Extending vertically through the arms 4 and 5 of the bracket is the vertical shaft 6, having the hand wheel or handle 7 upon its upper end above the arm 5 and the ratchet wheel 8 below the wheel 7. Pivoted to the arm 5 adjacent the ratchet wheel 8 of the shaft 6 is the pawl 9, which is normally engaged with the teeth of the ratchet wheel 8, preventing the rotation of the wheel 7 in a backward direction.

Secured to the shaft 6 in the arms 4 and 5 of the bracket are ends of the wires 10, which have their opposite ends secured in

the wire fence grippers 11. The wire fence grippers 11 are preferably U-shaped and have their outer parallel ends turned upon themselves, as shown at 12. The wires 10 are secured in the curved portion of the U-shaped wire fence grippers, while the turned ends 12 of said grippers are adapted for engagement with the fence wire. Each wire fence gripper 11 is adjustably secured upon the slotted spacing bar 13, by means of a bolt 14 having a nut 15 secured upon one end, thus binding the gripper 11 against the bar 13. The bar 13 is substantially oblong in shape and is provided with an elongated slot practically its full length, through which slot bolts 14 are positioned.

Two or more of the spacing bars 13 are usually employed, said spacing bars being connected by an extra bolt 16 with a suitable nut 17, said bolt 16 passing through the slots in two of the spacing bars. When two or more of the spacing bars 13 are employed, a bolt 14 may be passed through the slots at the overlapping ends of the bars, to position one of the grippers 11 at the center of the long adjustable bar formed of a number of spacing bars 13.

It will be seen that by the use of the above described form of slotted spacing bars 13 and the wire grippers 11, the latter may be adjusted in relation to one another along the length of the spacing bar, which is held during the operation of the wire stretcher in a vertical position.

In employing this wire stretcher the auxiliary post 1 is driven in the ground a suitable distance from the post to which the wire fence is to be secured and the inturned ends 12 of the wire grippers 11 are engaged with the vertical edge of the wire fence, (as illustrated) and the shaft 6 is rotated in the proper direction to wind the wires 10 thereupon, said shaft being rotated by means of the wheel 7. The pawl 9, being engaged with the teeth of the ratchet wheel 8, will allow the shaft 6 to be rotated in proper direction, said pawl riding over the teeth of the ratchet wheel as they pass and catching back of each tooth, thus preventing the shaft from rotating in the opposite direction to allow the wire fence to draw away before being secured to the fence post. Thus it will be seen that I have provided a wire fence stretcher which will be effective in its operation and which is simple in construction and cheap to manufacture. It will also be

seen that this stretcher may be employed for stretching wire fences of various types and may also be employed for other wire stretching purposes. It will further be seen that 5 this device is composed of an extremely small number of parts and that the parts are so formed and assembled as to present a strong and durable stretcher.

What I claim is:

10 1. A device of the class described comprising a longitudinally adjustable spacing bar, adjustable grippers spaced upon said adjustable spacing bar, means for securing said grippers upon said adjustable spacing bar and adjusting them in relation to one another, said grippers being adapted for engagement with a device to be stretched, and means for drawing the adjustable spacing bar and grippers to stretch the device with 20 which the grippers are engaged.

2. A device of the class described comprising a two-part longitudinally adjustable wire gripper carrying spacing bar, wire grippers adjustably secured upon said adjustable spacing bar and adapted to grip a 25

device to be stretched, and means for drawing the two-part adjustable spacing bar and the grippers carried thereby to stretch the device with which the grippers are engaged.

3. A device of the class described comprising a spacing bar, U-shaped wire grippers adjustably secured to one face of the spacing bar and spaced from one another, said U-shaped grippers having parallel ends turned upon themselves to receive and hold a vertical edge of a device to be stretched, means for securing said wire grippers in adjusted position and in spaced relation to one another, and means for moving the spacing bar and grippers to stretch the device with which the grippers are engaged.

In testimony whereof I have signed my name to this specification in the presence of two subscribing witnesses.

LOUIS HANSON.
